UNITED STATES PATENT OFFICE.

MATHEW HILGERT, OF NEW YORK, N. Y.

SHOE.

Application filed November 23, 1921. Serial No. 517,248.

This invention relates to shoes and particularly to the provision therein of a filler piece which, while particularly conducive to the comfort of persons having abnormal or tender feet, is at the same time helpful to all persons wearing shoes of the character usual in this and other civilized countries. An important factor in causing the tiring of human feet, even when wearing shoes which according to present day standards are considered to be a good fit, is the friction caused by the relative sliding movement of the sole of the foot and the insole of the shoe as the sole is flexed during walking. If the upper surface of the insole of the shoe has become roughened or cracked, as it frequently does before the shoe is otherwise worn out, the friction is much increased. Indeed it is a common experience when putting on a pair of shoes which have been worn and then laid aside for any considerable length of time to find that the upper surface of the insole is in such a condition that the shoes can be worn only with considerable discomfort if at all.

It is an object of the present invention to minimize, and so far as possible to eliminate, friction between the sole of the foot and the shoe structure. With this in view the invention contemplates the insertion in a shoe of a filler piece, the whole or at least the forward portion of which is not secured to the shoe, and which has its upper surface shaped to conform to the sole of a human foot, the filler piece being shorter than the inside length of the shoe so that as the shoe is flexed during walking the forward portion of the filler piece may move relatively to the forward portion of the insole of the shoe without buckling or wrinkling. The upper surface of the insole and the lower surface of the filler piece will slide one on the other as the shoe is flexed while there will be no relative longitudinal movement of the foot and the filler piece with the result that any roughness on the upper surface of the insole will be imperceptible to the foot and the shoe will remain at all times comfortable, assuming, of course, that it is a proper fit, even though in the course of time the insole should crack or otherwise disintegrate.

In the illustrated embodiment of the invention the filler piece is shown as formed with a cupped heel seat portion, an arch

supporting shank portion, and a balance piece, so-called, which underlies one side of the ball portion of the foot of the wearer so as to correct the tendency of the foot to roll in the direction of the balance piece. Experience has shown that a large majority of feet tend to roll outwardly and a small though appreciable minority tend to roll inwardly, the balance piece thus in the majority of cases being upon the outside, that is upon the left side of a left shoe and the right side of a right shoe, while in only a minority of cases will the balance piece be upon the inside, that is upon the left side of a right shoe and the right side of a left shoe. With the filler piece thus formed and of the length indicated, the rear portion thereof will be stationary in the heel and shank portion of the shoe while there will be relative movement of the forward portion of the filler piece and the insole as the shoe flexes, the foot thus being supported in a natural position and friction being eliminated in a manner which is very comfortable to the wearer.

With the above and other objects and features in view the invention will now be described in connection with the accompanying drawings, which disclose a shoe embodying the present invention, and pointed out in the claims.

In the drawings,

Fig. 1 is a cross-sectional view of a shoe containing the filler piece, the upper of the shoe being cut away upon a plane substantially parallel to the sole of the shoe;

Fig. 2 is a perspective view of the filler piece, with parts broken away, removed from the shoe; and

Figs. 3 and 4 are side elevations with the forepart of the shoe in section showing the relation of the filler piece to the insole of the shoe when the shoe is resting flat upon the ground and when it is flexed as in walking, respectively.

The shoe of the present invention may advantageously be manufactured upon a last of a form such as that of my prior United States Patent No. 1,120,490, granted Dec. 8, 1914, the upper of the shoe thus being made of such dimensions and form as to allow for the placing of a filler piece 6 within the otherwise completed shoe. The upper surface of the filler piece 6 is shaped to conform to the sole of a human foot, being for this

purpose provided with a heel seat portion 8 cupped both longitudinally and transversely (as shown in Fig. 2), an arch supporting shank portion 10, and a balance piece 12 positioned usually beneath the outside part of the ball portion of the foot to correct the usual "out-roll" of the foot, but if the shoe is intended for a person whose feet have an "in-roll" then upon the inside of the ball portion. This filler piece, or "foot mold" as it may be called, provides a smooth supporting surface for the foot through which the heel nails of the shoe will never penetrate. Because it is shaped to the sole of the foot it causes the weight of the wearer to be distributed over substantially the whole area of the sole portion of his foot so that the bones, muscles and ligaments of the foot are enabled to function substantially as they do when a person having a normal foot is walking barefoot. At the same time the foot is supported by the shoe and filler piece in a manner which is most helpful to persons having weak or sensitive feet.

To permit the filler piece, which may be made of any suitable flexible material, to bend without wrinkling or buckling as the shoe is flexed in walking, the filler piece is made of a length somewhat shorter than the inside length of the shoe as clearly shown at 14 in Figs. 1 and 3. With this same object in view the toe portion of the filler piece is shaped to taper somewhat more abruptly than that of the insole 16 of the shoe in which it is inserted, this more abruptly tapered portion extending from a point 18 forward of the ball line of the foot to the forward extremity. When a filler piece of this character is used in but not attached to a shoe, the tendency of the filler piece to move relatively to the foot is substantially less than the tendency of the forward portion of the filler piece to move with respect to the insole of the shoe as the shoe is flexed so that the foot and the filler piece move as a unit with respect to the insole of the shoe, the forepart of the filler piece creeping relatively to the sole, and all possibility of discomfort due to friction as the foot moves relatively to the insole of the ordinary shoe is eliminated. To promote this effect the lower surface of the filler piece is made smooth, as shown in Figs. 1, 2 and 3, and the upper surface of the insole of the shoe should also be as smooth as practical and talcum or other appropriate powder may be sprinkled between the filler piece and the insole. However even if the insole should become cracked after the shoe has been in use for some time, or after the shoe has been lying idle, still the formation of the filler piece and its capability of flexing without wrinkling as its forward portion moves over the insole are such as to protect the foot and render the shoe comfortable under circum-

stances which otherwise would render it practically unwearable.

Having described my invention, what I claim as new and desire to secure by Letters Patent of the United States is:

1. A shoe having a detached, non-metallic, filler piece inserted therein, said filler piece having a smooth lower surface and being of a length substantially shorter than the inside length of the shoe and having a taper at its forward extremity more abrupt than that of the insole of the shoe so as to permit the forepart of the filler piece to slide relatively to the insole of the shoe without wrinkling or buckling as the sole of the shoe is flexed during walking.

2. A shoe having a filler piece inserted therein with at least its forward portion detached from the shoe and having its upper surface shaped to conform to the sole portion of a human foot and of a length a little shorter than the inside length of the shoe so as to permit relative sliding movement of the forepart of the filler piece and the forepart of the insole of the shoe as the sole of the shoe is flexed during walking.

3. A shoe having a filler piece inserted therein with at least its forward portion detached from the shoe and having its upper surface shaped to conform to the sole portion of a human foot and provided with a heel seat portion cupped both longitudinally and transversely, the filler piece having a smooth lower surface and being of substantially less length than the inside length of the shoe so as to permit relative sliding movement of the forepart of the filler piece and the forepart of the insole of the shoe as the sole of the shoe is flexed during walking.

4. A shoe having a filler piece inserted therein with at least its forward portion detached from the shoe and having its upper surface shaped to conform to the sole of a human foot, the filler piece having a balance piece positioned to underlie one side of the ball portion of the foot of the wearer so as to counteract the tendency of the foot to roll in the direction of the balance piece, and being of a length substantially shorter than the inside length of the shoe to permit relative sliding movement of the filler piece and the insole of the shoe as the sole of the shoe is flexed during walking.

5. A shoe having a detached filler piece inserted therein provided with a cupped heel seat portion and a balance piece arranged to underlie one side of the ball portion of the foot of the wearer so as to correct the tendency of the foot to roll in the direction of the balance piece, the filler piece being of substantially less length than the inside length of the shoe so as to permit relative sliding movement of the filler piece and the sole of the shoe as the sole of the shoe is flexed during walking.

6. A shoe having a filler piece inserted therein having a heel seat portion cupped both longitudinally and transversely, an arch supporting shank portion, and a balance piece arranged to underlie one side of the ball portion of the foot of the wearer to correct the tendency of the foot to roll in the direction of the balance piece, the filler piece having at least its forward portion 10 detached from the shoe and being of a length substantially less than the inside length of the shoe to permit relative sliding movement of the forward portion of the filler piece and the insole of the shoe as the sole of the shoe 15 is flexed during walking.
7. A shoe having a filler piece therein shaped to conform to the sole portion of a
- human foot and of a length a little shorter than the inside length of the shoe so as to permit relative movement of the forepart of the filler piece and the forepart of the sole of the shoe as the sole of the shoe is flexed during walking.
8. A shoe having a filler piece therein of a length a little shorter than the inside length of the shoe, so that the filler piece and the sole of the shoe may move relatively to one another as the sole of the shoe is flexed during walking, without relative movement of the filler piece and the foot of the wearer. 30

In testimony whereof I have signed my name to this specification.

MATHEW HILGERT.
